(57) **CLAIM**

The ornamental design for a dispenser as shown and described.

DESCRIPTION

FIG. 1 is a perspective view of a dispenser including a sensor and/or fill level indicator according to a first embodiment of the claimed design.

FIG. 2 is an enlarged top view of the dispenser of FIG. 1. FIG. 3 is a perspective view of a dispenser including a sensor and/or fill level indicator according to a second embodiment of the claimed design.

FIG. 4 is an enlarged top view of the dispenser of FIG. 3. FIG. 5 is a perspective view of a dispenser including a sensor and/or fill level indicator according to a third embodiment of the claimed design; and,

FIG. 6 is an enlarged top view of the dispenser of FIG. 5. The dash-dash broken lines in the drawings illustrate portions of the dispenser that form no part of the claimed design.

The dispenser in FIGS. 5–6 is shown with symbolic breaks in its length and width. The appearance of any portion of the article between the break lines forms no part of the claimed design. The dash-dot break lines form no part of the claimed design.

Portions of the dispenser, with the exception of the top, as viewed opposite to the perspective view shown by FIG. 1 are the same as shown by FIG. 1.

Portions of the dispenser, with the exception of the top, as viewed opposite to the perspective view shown by FIG. 3 are the same as shown by FIG. 3.

Portions of the dispenser, with the exception of the top, as viewed opposite to the perspective view shown by FIG. 5 are the same as shown by FIG. 5.

(Continued)

The vertical solid lines at the body of the dispenser in FIGS. 1, 3, and 5 illustrate claimed portions of the dispenser. The claim extends to the end of each vertical solid line and includes the surface portion shown between the vertical solid lines.

1 Claim, 6 Drawing Sheets
